OHIO.

CAN-TESTER.

1,144,081.

Specification of Letters Patent. Patented June 22, 1915.

Application filed October 3, 1913. Serial No. 793,144.

To all whom it may concern:

Be it known that we, JAMES W. VORIS and CLYDE E. HOVER, citizens of the United States, and residents of the city of Norwood, in the county of Hamilton and State of Ohio, have invented certain new and useful Improvements in Can-Testers, of which the following is a full, clear, and exact description, reference being had to the accompanying drawings, forming part of this specification.

The object here is to provide a tester for tin cans or the like, which will select from a lot of cans those which are not airtight and discard such cans at a certain point, while delivering the cans which are absolutely sound at another point. This is accomplished by providing a rotating holder to which the cans are fed, which receives the cans in rotation, tests them by a partial vacuum, which releases the ones with air holes at one point and the sound ones at another; and generally and specifically by that certain construction and arrangement of parts to be hereinafter particularly pointed out and claimed.

In the drawings, Figure 1 is a front elevation of the device showing the cans fed in from the right hand side. Fig. 2 is a central vertical section of the upper portion of the device shown in Fig. 1. Fig. 3 is an enlarged vertical section of the outer portion of the vacuum tubes showing the valves therein. Fig. 4 is a central section of the wheel and vacuum box with the balance of the view in perspective. Fig. 5 is a top plan view of the vacuum box. Fig. 6 is a rear elevation of a portion of the wheel. Fig. 7 is a perspective of one of the contact pieces for the cans to bear against. Fig. 8 is a side elevation of the device for pressing the cans on the contact pieces.

1 is the pedestal or standard upon which the machine is mounted, and 2 is the hub and 3 the rim of the wheel which carries and delivers the cans. As an axle for the hub of the wheel, the vacuum box 4 is provided, which is cylindrical in shape with a flattened portion 5 at one side. The air is exhausted from this box through the tube 6. The turning of the wheel, which is not to be done with too great rapidity, may be accomplished by a belt, gearing, crank handle or any desired means. This feature constitutes no part of the invention and it

has not been thought necessary to illustrate it. There are shown four spokes 7, 7, of the wheel, although more could be used, or less as desired. These spokes do not interfere with the vacuum pipes which are arranged radially in the wheel behind the spokes. The vacuum pipes are of two kinds, primary pipes 8 and secondary pipes 9, one of each, for each can receiver. The hub of the wheel rests with the weight of the wheel on the vacuum box, and since both of them are round a practically airtight contact is maintained at all points, except at the flattened portion 5 of the box. The tubes extend through the hub, and the box has a peripheral slot 10 to register with the secondary tube and a small slot 11 for the primary tube. Except at the flattened end the secondary tube is thus constantly in communication with the vacuum. The primary tube, however, communicates with the vacuum at one point only. The location of the slot 11 determines this point and the vacuum is retained in the tube as hereinafter described by the airtight contact of the hub 2 with the box 4. The tubes 8 and 9 extend radially to the rim of the wheel where they join and communicate with a passageway 12 in the rim, running from the back to the front of the wheel. At the front outlet of the passageway on the front face of the wheel is located the rubber disk 13 (Fig. 7), with a hole in it for the passageway. Located underneath this disk on the face of the wheel is the semi-cylindrical holder 14. This construction is of course duplicated as many times as the circumference of the wheel and size of parts will allow. The tin cans 16 to be tested are fed into the holders 14, in this instance from an inclined chute 15. The cans 16 are so placed on the chute that their open ends lie toward the front face of the wheel. They will of course be picked off the carrier, one by one, by the holders 14, and in the absence of any means of attachment would fall out of the holders as soon as they passed the top of the wheel. The open end of the cans, however, come opposite the opening in the disk 13, and the suction from the vacuum chamber is designed to hold them in place, for testing purposes up against the disks.

The small slot 11 in the vacuum box is located just beyond the corner of the flat portion of the box. The tubes 8 and 9 and 110

their passageways through the hub are so positioned that the primary tube reaches its slot 11 before the secondary tube 9 has passed the open space left by the flat side 5 of the box (Fig. 2). A standard 23 is provided which carries a segmental head 24 sliding in mortises in the head and regulated by the screw 25. The inner surface of the head has a rounded portion 26, and the parts 10 are so arranged as to present the portion 26 to the front of the wheel rim 3, with the nearest point of its rounded surface at the proper distance to press the cans as they leave the holders hard up against the disks 15 13 (Fig. 8). The box is so placed and its flat side so situated that just as a tin can is pressed against the disk 13, the primary tube of that holder will come into registration with the slot 11. The can 16 will then 20 be sucked against the disk 13 and will remain there during a revolution of the wheel, owing to the airtight connection of the hub with the vacuum box, although the primary tube is at once disconnected from the vacuum. 25 As soon as the primary tube reaches the air space left by the flat side 5, the can will of course be released. The chute 17 will then receive the can. This is what occurs if the can in question has no small leak 30 of any kind. That is to say, a can which is delivered at 17 is a can tested and found to be without leaks. The suction line in the primary tube 8, before it reaches the can, as has been said, goes through a passageway 35 12. This passageway is formed by an L-tube which also communicates with a valve chamber 19. The tube 9 enters this chamber at the opposite side to the tube 18, and a valve disk 20 in the chamber is located to 40 seat in the inlet of either tube. On the face of this valve disk 20 are valve rods 21, 21, which raise valves 22, 22, in the chamber leading to the open air. These parts are so arranged that when the valve disk 20 is 45 seated in the tube 18, thus closing the chamber from the passageway 12, the valves 22, 22, to the open air will be closed. When the disk 20 is raised and the valves 22 opened, then the tube 18 to the chamber will let atmospheric air into the passageway 12; 50 which atmospheric air does not get into the tube 9, because its entrance to the chamber will be closed by the disk 20.

Going back to the point where a can is 55 placed on a holder: The step has been explained as to how the can is seized and held. When this has taken place, there is no vacuum in tube 9, as has been explained. The valve 20 is bound to be closed, then as a 60 can is seized. But just after it is seized the tube 9 communicates with the vacuum. This will not raise the valve because the vacuum in the passageway 12, in the can and in the tube held airtight, balances the vacuum in 65 the tube 9 and the chamber 19. As soon as

any air, even a very small amount leaks into the can, this balance will be destroyed. The valve will rise, close off the tube 9 and let air into the can holding parts. The can is thus released. Owing to the shape of the 70 holders, the defective cans are bound to be carried to the top of the wheel. After passing this point, they will fall off if release has taken place. The usual leakage of such cans is small, and the wheel must not turn 75 too rapidly. We find that all of the defective cans will have come off at about the point in the drawings where the chute 23 is shown, upon a moderate rotation of the wheel. The defectives are then conducted 80 away from the machine by this chute.

It can now be seen that a sure test and a delicate test can be applied to the cans by the machine. All use of unhygienic water tests is done away with. The vacuum may 85 be made very powerful without destroying the effectiveness of the machine. A very slight inequality in pressure in the secondary and primary tubes will work the releasing valve. In this way we accomplish strength 90 without loss of sensitiveness. It is also plain that constant attention of an operator is not required, and that a wide range in size of cans may be tested without the slightest alteration except of the head 24. So long 95 as the rubber contact piece is large enough and the passageway 12 is not so high as not to communicate with the inside of a can held on the holder, the machine will work perfectly. This is because the attachment 100 of the cans to the machine is accomplished by the vacuum.

In mentioning certain shapes of tubes, materials of parts and so on, it has not been desired to limit ourselves to the specific uses 105 detailed, nor in any way by specific uses to limit the scope of the claims.

Having thus described our invention, what we claim as new and desire to secure by Letters Patent, is:—

1. A tester for cans and the like, comprising a revoluble can receiving member, and a stationary member on which the revoluble member abuts, means for putting the stationary member under reduced pressure, a 115 series of radial tubes on the revolving member communicating at the outer end with cans to be tested, and at the inner end opening against the stationary member, and a slot at one point in the stationary member, 120 located so as to communicate with the inner ends of the radial tubes, said slot being of a size to communicate with the said tubes at one position only of the revolving member, and means for holding the cans against 125 the outer ends of the tubes at this position, for the purpose described.

2. A tester for cans and the like, comprising a revoluble can receiving member, and a stationary member on which the revoluble 130

- member is journaled, means for putting the stationary member under reduced pressure, a series of radial tubes on the revolving member communicating at the outer end 5 with cans to be tested, and at the inner end opening against the stationary member, and a slot at one point in the stationary member, located so as to communicate with the inner ends of the radial tubes, said slot being of 10 a size to communicate with the said tubes at one position only of the revolving member, and means for holding the cans against the outer ends of the tubes at this position, for the purpose described.
- 15 3. A tester for leakage in cans and the like, comprising a revolving can receiving member, a member under suction on which it revolves, means for putting said member under suction, openings therein, a passageway in the receiving member registering with one of the openings to apply initial suction to the cans, a valve in said member, and a passageway from the valve registering with another opening in the suction 20 member, for the purpose described.
- 25 4. A tester for leakage in cans and the like, comprising a cylindrical vacuum box, a wheel, having a rim adapted to receive the cans, and a hub adapted to revolve on the box, radial tubes running through the hub, out, and through the rim, the box having openings to register with the tubes positioned so as to apply suction to the cans when received on the rim, and means for releasing the suction upon leakage of air into the cans, for the purpose described.
- 30 5. A tester for leakage in cans and the like, comprising a cylindrical vacuum box, a wheel, having a rim adapted to receive the cans, and a hub adapted to revolve on the box, primary radial tubes running through the hub, out and through the rim, secondary tubes running through the hub and communicating with the primary tubes, a valve 35 at the point of communication, and means controlled by said valve for admitting atmosphere to the primary tubes, upon slight inequalities of suction between the two tubes.
- 40 6. A tester for leakage in cans and the like, comprising a cylindrical vacuum box, a wheel, having a rim adapted to receive the cans, and a hub adapted to revolve on the box, primary radial tubes running through the hub, out and through the rim, secondary tubes running through the hub and communicating with the primary tubes, a valve 45 chamber at the point of communication and a valve disk operating in said chamber 50 adapted to seat in either tube, and valves controlled by said disk for admitting the atmosphere to the chamber when said disk

is raised from its seat in the primary tube, upon slight inequalities of suction between the tubes.

65

7. A holding and releasing device for automatic can testers, comprising a passageway to the can receiver through which suction is applied to the can to hold it on the receiver, a primary tube for suction on the can, connections therefrom to the passageway, a secondary tube under partial vacuum substantially equal to that in the primary tube, connections therefrom to a valve chamber, a valve chamber, connection from the valve chamber to the passageway, a valve in said chamber adapted to seat in either connection therefrom, and valves to the atmosphere controlled by said two-way valve positioned to open when the latter valve is off of its seat in the passageway.

8. A holding and releasing device for automatic can testers comprising a source of suction to hold the can, a secondary source of suction, a valve balanced between the two sources, and means controlled by said valve for admitting atmosphere to the holding source upon inequality arising between the sources.

9. A tester for leakage in cans and the like, comprising a can receiving member, a source of suction for retaining cans on the receiving member, means for maintaining and for automatically releasing said suction at a given point, and a valve between the atmosphere and the source of suction and means for releasing said valve upon leakage of air into the can.

10. A tester for leakage in cans and the like, comprising a can receiving member, a source of suction for retaining cans on the receiving member, means for retaining and automatically releasing said suction at a given point, a secondary source of suction, a valve closing the two sources of suction from each other, and means on the valve to admit atmosphere to the can holding suction, when leakage into the can destroys the balance between the suction.

11. A tester for leakage in cans and the like, comprising a revolving can receiving member, a pressing member having a rounded surface and adjustable to press a can of any desired size against the face of the receiving member, means for retaining cans on the receiving member by suction and means for releasing the suction upon leakage of air into the cans.
